W. J. BARBER.
COMBINED MOP HOLDER AND WRINGER.
APPLICATION FILED JUNE 27, 1911.

1,004,965.

Patented Oct. 3, 1911.

UNITED STATES PATENT OFFICE.

WILLIAM J. BARBER, OF MARIETTA, OHIO, ASSIGNOR OF THREE-EIGHTHS TO
WILLIAM H. BARBER, OF MARIETTA, OHIO.

COMBINED MOP HOLDER AND WRINGER.

1,004,965.

Specification of Letters Patent.

Patented Oct. 3, 1911.

Application filed June 27, 1911. Serial No. 635,601.

To all whom it may concern:

Be it known that I, WILLIAM J. BARBER, a citizen of the United States, residing at Marietta, in the county of Washington and State of Ohio, have invented new and useful Improvements in Combined Mop Holders and Wringers, of which the following is a specification.

The primary object of the invention is the provision of a mop holder and wringer in which the mop cloth may be held in proper position for mopping the floor, and can be wrung out for freeing the same from surplus water.

15 Another object of the invention is the provision of a mop holder and wringer in which the cloth thereof may be distended and retracted during the mopping of a floor, for the thorough cleaning thereof, and also that 20 will permit the wringing of the cloth without the splashing of water contained therein, and at the same time avoiding the necessity of manually handling the cloth for this purpose.

25 A further object of the invention is the provision of a combined mop holder and wringer of this character which is simple in construction, thoroughly reliable and efficient in operation, and inexpensive in manufacture.

30 With these and other objects in view, the invention consists in the construction, combination and arrangement of parts, as will be hereinafter more fully described, illustrated in the accompanying drawings, and pointed out in the claims hereunto appended.

35 In the drawings: Figure 1 is a side elevation of a mop and wringer constructed in accordance with the invention. Fig. 2 is a top plan view thereof. Fig. 3 is a side elevation, showing the cloth twisted for the wringing of surplus water therefrom. Fig. 4 is a vertical longitudinal sectional view 40 of the device. Fig. 5 is a transverse sectional view of the device.

45 Similar reference characters indicate corresponding parts throughout the several views of the drawings.

50 Referring to the drawings by numerals, the combined mop holder and wringer comprises a handle 5, the same being engaged in a ferrule or tubular socket extension 6, the latter being formed with spaced parallel

55 ears 7, to which is pivotally connected a

slide 8, the same being formed with upturned ears 9, through which are passed pivots 10, the same being also passed through the depending ears of the ferrule or socket extension.

Engaged in the slide 8 is a mop holder, comprising a wire frame 11, the latter being formed preferably of wire bent to provide spaced side limbs 12 uniting front and rear end loops 13 and 14, respectively. Passed 60 through the front loop 13 is an endless mop cloth 15, the same being also passed through a loop 16 formed on a turning shank 17, the latter being pivoted in the ferrule and the handle engaged therein, and terminates in 65 a right angular crank handle 18, the shank 16 being journaled at a point rearwardly of the depending ears of the ferrule or socket extension, so that upon turning the crank handle 18 when the mop holder has been 70 swung to right angles to the axis of the handle 5, the mop cloth may be twisted and wrung, so as to free water therefrom, without manual handling of the mop cloth.

Formed in the side limbs of the mop 75 holder are abutment shoulders 19 which limit the forward movement of the slide 8 upon the said limbs, when the mop cloth is engaged with the floor, and by reason of the pivotal connection of the slide with the depending ears of the ferrule or tubular socket extension 6, the handle 5 may be raised and lowered for exerting the required pressure upon the mop cloth, during the mopping operation, the slide 8 being free to move 80 forwardly and rearwardly into contacting relation with the shoulders 19 and the rear loop 12.

85 From the foregoing, taken in connection with the accompanying drawings, it is 90 thought that the construction and operation of the invention will be readily understood, without requiring a more extended explanation.

95 What is claimed is:

1. A device of the class described, comprising a socket extension adapted to receive a handle, a slide pivotally connected to the socket extension at one side thereof, a mop holding frame slidably engaged in the slide, 105 a wringing device mounted in the socket member, and a mop cloth engaged with the mop holding frame and the said wringing device.

2. A device of the class described, com- 110

prising a socket extension adapted to receive a handle, a slide pivotally connected to the socket extension at one side thereof, a mop holding frame, slidably engaged in the slide, a wringing device mounted in the socket member, a mop cloth engaged with the mop holding frame and the said wringing device, and bends formed in the mop holding frame to limit the movement of the slide thereon.

3. A device of the class described, comprising a handle, a socket extension mounted upon one end of the handle and having spaced parallel ears projecting outwardly

from one side thereof, a slide member pivotally connected to the ears, a mop holder slidably connected in the slide and having loop ends, a mop cloth engaged in one of the loop ends, and means connected with the socket extension and engageable with the cloth for permitting the wringing thereof.

In testimony whereof I affix my signature in presence of two witnesses.

WILLIAM J. BARBER.

Witnesses:

ASA E. WARD,
W. H. BARBER.
